UNITED STATES PATENT OFFICE.

JOHN LIONEL SHAFER, OF JOPLIN, MISSOURI.

PUMP PACKING.

Application filed April 16, 1925. Serial No. 23,620.

This invention relates to packings for pumps.

An object of the invention is the provision of a pump adapted to be operated by fluid under pressure for pumping liquids and in which the stuffing boxes for the driven pistons of the pump are located exteriorly of the pump whereby the same may be readily removed, replaced or repaired.

10 This invention will be best understood from a consideration of the following detailed description, in view of the accompanying drawing forming a part of the specification; nevertheless it is to be understood 15 that the invention is not confined to the disclosure, being susceptible of such changes and modifications which shall define no material departure from the salient features 20 of the invention as expressed in the appended claims.

In the drawings:

Fig. 1 is a vertical section of a pump showing the packing or stuffing box in position.

25 Figure 2 is a view in perspective of the pump unit shown in Figure 1.

Figure 3 is a view in perspective of the sleeve forming part of the packing for the pump.

30 Referring more particularly to the drawings conduits 8 and 9 are respectively connected by means of elbows 23 with aligned pump cylinders 24 and 25, respectively. The inner ends of the aligned cylinders 24 35 and 25 are respectively screwed into a threaded opening in a housing 26 which is adapted to be bolted as shown at 27 to a closure plate 28. The closure plate is secured to a flanged opening 29 formed at 40 each side of the delivery pump housing 30. The plate 28 is provided with a hub 31 having a reduced boss section 32 and a shoulder 33 located between the hub portion 31 and the boss 32 to form a seat for a compression 45 spring 34. The boss 31 is provided with a pair of threaded passages 35 into which are adapted to be screwed a threaded bolt 36 for adjusting a packing gland 37.

50 This packing gland as shown in Figure 3 is formed by a plate 38 having pairs of ears 39 extending in opposite directions and adapted to receive the portion 40 of the bolt 36 which is located between a pair of flanges 41 and 42 integrally formed with the bolt 36. Extending inwardly from the plate 38 is a cylindrical portion 43 which is

adapted to embrace a piston 44 and has its outer free end bevelled as shown at 45 to engage a packing 46 surrounding the piston 44 and located within an enlarged recess 60 within the hub 31. The outer ends of the bolts pass through openings protected by packing 47 in the housing 26. The outer projecting ends of the bolts are made rectangular in cross section as shown at 48 in 65 order that the same may be conveniently engaged by a suitable tool for rotating said bolts.

As shown in Figure 1 a pair of pistons 44 and 44^a are integrally formed with a connecting rod 49 which is operable within the main pump chamber 50. The connecting rod is provided with an annular flange 51 which is perforated to receive bolts 52 for locking the two sections 53 and 54 of the 75 main pump piston generally designated by the numeral 55. The piston 55 is adapted to be cushioned by the springs 34 at the opposite limits of the strokes of the piston.

In the preferred form the pistons 44 and 44^a and the integrally formed connecting rod 49 are provided with a longitudinal passage 56 passing entirely through the pistons and connecting rod and opening into chambers 57 at the outer ends of the pistons. These 80 chambers are closed by valve cages 58 which have a central passage to receive a valve stem 59. A spring 60 is located within the chamber 57 and is adapted to act upon a valve 61 carried by the stem 59. These valves 90 close the opposite ends of the port upon the suction stroke of each piston. The projecting stems 59 are adapted to be engaged by a lug 62 mounted in horizontal alignment with the stems and screwed into threaded 95 bosses 63 formed integrally with the elbows 23 and is adapted to engage a valve stem 59 when either of the pistons 44 and 44^a has been moved to its outer limit of stroke for forcing the valve 59 open.

100 The elements are assembled as follows:

With the plungers 44 and 44^a in place the cover plate 28 is connected to the pump casing 30 by means of bolts. Packing 46 is disposed in position within the hub 31 and embracing the pistons 44 and 44^a when the gland 37 is positioned in place on the respective pistons and the bolts 36 are screwed into the respective threaded passages 35 with the flanges 41 and 42 embracing the opposite 105 faces of the ears or lugs 39. The bolts are then operated by a suitable tool engaging

the outer end 48 of said bolts until the gland 37 is moved into its proper position when the housing 26 is bolted to the cover plate 28. The cylinders 24 and 25 are then 5 screwed into the threaded openings in the outer ends of said housings. By adjusting the bolts 36 the proper pressure may be maintained upon the packing 46 to prevent loss of fluid at these points and it will be noted 10 that these packing boxes are so constructed that they are formed upon the outer portion of the pump casing 30 so that they may be readily removed or corrected as the case may be.

15 The passage 56 in the pistons 44 and 44^a is designed to relieve pressure of the excess of liquid in either of the conduits 8 or 9 so that when, for instance, the piston 44^a reaches the limit of its stroke the lug 62 will 20 engage the stem 59 and operate valve 61 thereby opening said conduit to cylinder 25 so that the liquid may pass from said cylinder through the conduit 56 and into the cylinder 24 which has been on its suction 25 stroke. Upon the reverse operation of the pistons the lug 62 adjacent piston 44 will operate valve stem 59 and open said valve at the outer limit of the stroke of said piston whereby the pressure in said cylinder will 30 be relieved and a portion of the liquid will be transferred through the conduit 56 to piston 25.

What I claim is:

1. In a fluid pressure pump, a packing 35 comprising a plate having an inwardly pro-

jecting hollow boss, the end of the boss being provided with an inwardly turned annular flange, packing material located in the hollow boss, a cylindrical gland having the inner end thereof in engagement with the packing material, a cover embracing the gland and provided with a flange secured to the plate, said gland having oppositely disposed pairs of ears, bolts having threaded engagement with the boss and provided with spaced rings 40 adapted to engage opposite sides of the ears, with the bolts at these points being received between said ears.

2. In a fluid pressure pump, a packing 45 comprising a plate having an inwardly projecting hollow boss, the end of the boss being provided with an inwardly turned annular flange, packing material located in the hollow boss, a cylindrical gland having the inner end thereof in engagement with the packing 50 material, a cover embracing the gland and provided with a flange secured to the plate, said gland having oppositely disposed pairs of ears, bolts having threaded engagement with the boss and provided with spaced rings 55 adapted to engage opposite sides of the ears, with the bolts at these points being received between said ears, said cover being cup-shaped and provided with passages through 60 which the free ends of the bolts are inserted, said bolts projecting beyond the cover and provided with means adapted to be gripped with a suitable tool for rotating said bolts.

JOHN LIONEL SHAFER.
